CLAIM

We claim the ornamental design for a kit bag, as shown and described.

DESCRIPTION

FIG. 1 is a front isometric view of a kit bag.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines depict portions of the kit bag that form no part of the claimed design.
